HEADER SUPPORTED WALL FOR BOILERS

Louis H. Hosbein, Glencoe, Ill., assignor to M. H. Detrick Company, Chicago, Ill., a corporation of Delaware

Application September 13, 1947, Serial No. 773,760

4 Claims. (Cl. 122—510)

1

My invention relates to boiler wall constructions, and more particularly to a pressure part supported wall for boilers.

In boilers it has been customary to mount the walls of refractory material on a framework that was entirely independent of the boiler structure. This necessitated the use of a very large amount of steel for supporting the wall, and it is a purpose of my invention to provide a mounting for walls for boilers that eliminates a large portion of the steel frame structure that was previously necessary.

It is a particular purpose of my invention to provide a pressure part supported wall for boilers whereby about half the weight of the steel that was previously required is eliminated and whereby the structure is considerably simplified to reduce the expense of construction thereof, the engineering work as well as the erection cost and the cost of the steel being reduced by my simplified mounting for the frame members for supporting the walls of boilers.

It is a specific purpose of my invention to provide in combination with a boiler having a pressure part, a wall of refractory members supported on or by said pressure part, said wall being, preferably, sectionally supported by means of a framework that comprises upstanding frame members supported by the pressure part and on which the sectionally supported wall is mounted.

My invention contemplates the use of boiler drums, headers and similar tubular members forming part of the boiler structure as a portion of the framework, by securing certain of the frame members directly to such boiler parts, as above referred to, and the provision of means in the connections allowing for a limited movement to compensate for the expansion of the boiler structure when the parts become hot.

One of the important purposes of my invention is that by utilizing my improved wall structure a tighter wall can be obtained because the spacing of the columns or upstanding members will increase when the drums and headers or similar parts to which the same are secured become hot, which would result in a general expansion of the wall that would be taken up by the slight breathing in each section between the columns rather than by providing slip seals between the wall and other parts, such as the roof and floor, at which all the expansion would otherwise have to be compensated for. By hanging the arch at the top of the wall and at the boiler drum, the seals between this arch and the drum can be permanent instead of a sliding seal, thus further providing a tighter structure.

2

Other objects and advantages of my invention will appear as the description of the drawings proceeds. I desire to have it understood, however, that I do not intend to limit myself to the particular details shown or described, except as defined in the claims.

In the drawings:

Fig. 1 is a vertical sectional view, partly broken away, of a wall constructed in accordance with my invention, showing fragments of the floor and roof.

Fig. 2 is a fragmentary detail sectional view on a somewhat enlarged scale, and

Fig. 3 is a fragmentary vertical sectional view 15 through a boiler construction embodying my improved wall construction, showing a drum for supporting certain of the frame members.

Referring in detail to the drawings, in Fig. 1 is shown a boiler structure in which there are 20 headers 10 and 11 between which the tubes 12 extend, said tubes being secured to the headers in a well known manner. A bracket 13 is provided on the header 10, being secured thereto by welding, and a bracket 14 is secured to the header 11 in a suitable manner, as by welding. Vertically extending frame members 15 are secured to the brackets 13 and 14, the brackets 13 being secured to the frame members 15 in fixed position by means of bolts 16. The bracket members 14 are 30 secured to the upper ends of the frame members 15 by means of bolts 17, which extend through openings in the frame members 15 and through slots 18 in the brackets 14 to thus provide for a limited relative sliding movement between the 35 brackets 14 and the frame members 15.

The refractory members 19, of which the wall is constructed, are shown more in detail in Fig. 2. Said refractory members are sectionally mounted on the framework, of which the vertically extending members 15 are the columns, by means of horizontally extending members 20, which are secured to the vertically extending frame members 15 and upon which hanger members 21 are mounted, which support the refractory members 19 sectionally, that is, each of the hanger members 21 supports a plurality of vertically adjacent refractory members 19. The specific construction of the sectional supporting means may be varied and does not form part of my invention.

50 The hanger members are protected from the heat to which the refractory members 19 are subjected by means of a layer of heat insulating material 22. The columns or upstanding frame members 15 may be of any desired shape, and in 55 the form of the invention illustrated these have lower ends 23 reduced in size to provide for the

outwardly directed portion of the wall that lies opposite the bends 24 in the tubes 12 at their lower ends.

The header 11 may also be provided with a bracket 40 welded thereto, which has a horizontally extending portion 41, that is provided with slots 42, through which the headed fastening elements 43 extend for securing the horizontal frame member 44 to said header so that there will be a limited longitudinal sliding movement between the frame member 44 and the bracket. Said frame member 44 extends between the header member 11 and a similar header member or other pressure part with which it is connected in a similar manner to that shown.

The frame members 44 are utilized to suspend the refractory members 45 by means of suitable hanger members 46 carried by the transversely extending members 47 or in any similar manner, and heat insulating material 22 is provided between the refractory members and the metallic hanger means carried by the frame members 44.

My invention further includes a framework for a sectionally supported wall, such as shown in Fig. 3, in which the drums 25 and 26 of the boiler are shown, which have the tubes 21 connecting the same. The refractory members 19 of the upstanding wall are sectionally supported in a similar manner to that previously described, by means of horizontally extending members 20 that are mounted on the vertically extending frame members 28, which are supported at their lower ends on any suitable support 35, such as a floor or foundation. The refractory members 19 of the arch shown in Fig. 3 are suspended from inclined frame members 29 and said arch is thus also sectionally supported. Said inclined frame members 29 may be connected together by means of transversely extending frame members 30, from which hanger brackets 21' are suspended.

The inclined frame members 29 are secured at their upper ends to the drum 26 by means of brackets 31 that are secured to the drum in any suitable manner, as by means of welding, and said inclined members are secured to the brackets 31 by suitable bolt-like members 32 that pivotally secure said inclined members to said brackets. Brackets 33 are secured to the lower ends of the inclined members 29 and said brackets are secured pivotally to the upper ends of the upstanding members or columns 28 by bolt-like members 34 that pivotally connect said brackets with the columns 28 and thus pivotally connect the members 28 and 29 together.

Suitable heat insulating material 36 is provided between the wall of refractories 19 and the metallic frame structure, and a similar insulating covering 37 is provided for the refractory members 19 of the arch, which are suspended from the hanger brackets 21' in a suitable manner. An insulating covering 38 is also provided for that part of the drum 26 that lies above the arch.

It will be obvious that when the boiler is in operation the heat existing in the parts 25 and 26 will cause expansion thereof and the pivot connections at 32 and 34 will permit a swinging of the inclined members 29 to compensate for this expansion of the parts and greater spacing of the members 25 and 26 from each other when the boiler structure expands as heating takes place, thus providing for a relative movement between the upstanding members 28 and the inclined members 29 of the framework.

It will further be noted that both in the use

of the headers 10 and 11 as framework members and of the drum 26 of the framework member, all heavy frame members extending horizontally for supporting the upstanding members 15 and 28, as the case may be, are entirely eliminated and thus the cost of construction is greatly reduced and much material is saved. In view of the fact that the pressure parts 10, 11 and 26 and similar pressure parts of a boiler are made of great strength to withstand the pressures in boilers of the character with which my invention is used, the same are of adequate strength to support the vertical frame members 15 and the inclined frame members 29 and the frame members 28 and the walls supported thereby, and accordingly no additional horizontal frame members are necessary for sectionally supporting the walls made up of the refractory members 19.

What I claim is:

1. The combination with a pair of spaced headers and tubes connecting said headers, of a wall of refractory members having a heat exposed face lying substantially in a plane in outwardly spaced relation to said tubes, a framework comprising frame members extending between said headers, individual means for supporting each frame member solely from said headers, each of said means comprising a member securing one end of said frame member in fixed position on one of said headers and means connecting the other end of said frame member to the other of said headers, each of said connecting means including a sliding joint, heat insulating material on the outer face of said wall, the outer face of said heat insulating material being spaced inwardly from said frame members, and wall refractory supporting members mounted on said frame members.

2. The combination with a pair of spaced headers and tubes connecting said headers, of a wall of refractory members having a heat exposed face lying substantially in a plane in outwardly spaced relation to said tubes, a framework comprising frame members extending between said headers, individual means for supporting each frame member solely from said headers, each of said means comprising a member securing one end of said frame member in fixed position on one of said headers and means connecting the other end of said frame member to the other of said headers, each of said connecting means including a sliding joint, heat insulating material on the outer face of said wall, the outer face of said heat insulating material lying in a plane spaced inwardly from said frame members, and wall refractory supporting means mounted on said frame members and extending from said frame members through said insulating material into engagement with said wall forming refractories.

3. The combination with a pair of vertically spaced headers and tubes connecting said headers, of a wall of refractory members having a heat exposed face lying substantially in a plane in outwardly spaced relation to said tubes, a framework comprising columns extending vertically between said headers, individual means for supporting each column solely from said headers, comprising a member securing the lower end of said column in fixed position to one of said headers and means connecting the upper end of said column to the other of said headers, each of said connecting means including a sliding joint, heat insulating material on the outer face of said wall, the outer face of said heat insulating material lying in a plane spaced inwardly from said col-

umns, and means mounted on said columns for supporting said refractory members on said columns.

4. The combination with a pair of vertically spaced headers and tubes connecting said headers, of a wall of refractory members having a heat exposed face lying substantially in a plane in outwardly spaced relation to said tubes, a framework comprising columns extending vertically between said headers, individual means for supporting each column solely from said headers comprising a bracket welded to one of said headers and rigidly connected with the lower end of said column, a bracket welded to the other of said headers, means securing the upper end of said column to said last mentioned bracket for limited longitudinal sliding movement relative thereto, heat insulating material on the outer face of said wall, the outer face of said heat insulating material being spaced inwardly from 20 said columns, and means mounted on said columns for supporting said refractory members on said columns.

LOUIS H. HOSBEIN.
